UNITED STATES PATENT OFFICE

2,677,211

READING STAND

Frank J. Luketa, Seattle, Wash.

Application September 30, 1950, Serial No. 187,719

8 Claims. (Cl. 45—82)

1

This invention relates to a reading stand, particularly one which is especially designed for use with, and to accommodate the various conditions found in a chair of the general type shown in various of my issued patents and pending applications, and which is characterized by the provision of a seat and a back, each independently tiltable about a transverse horizontal axis to various reclining or upright positions. Such a chair is shown, for example, in my Design application Serial No. D. 8,181, filed February 28, 1950. A reading stand of similar nature is shown in my copending application Serial No. 173,704, filed July 11, 1950.

Since the reading stand should support the reading matter directly in front of, that is, in the line of vision of the occupant of such chair, yet in such position it will be directly in his way should he attempt to arise from the chair, it is an object of the present invention to provide a mount for the reading stand swingable aside on a more or less upright axis, so that the reading stand may be supported generally from the side arm, which usually tilts with the chair's back, be located in operative or reading position directly in line with the occupant's line of vision, and yet may be swung wholly aside out of the way to permit the occupant to arise from the seat.

In a chair of this sort the side arms tilt with one of the main body-supporting elements, usually the back, and the reading stand is supported on one of the side arms, hence tilts with the latter. If the angular disposition and spacing of the reading stand relative to the eyes of the chair's occupant are correct when the back is comfortably upright, tilting the back farther towards the reclining position will soon dispose the reading stand overhead, in position where the book or other reading matter tends to fall onto the reader's face. It is customary to provide retaining means for the reading matter, to hold it to its stand, but this is not intended as the major support for the reading matter, nor is such a nearly vertical line of sight desirable, if it can be avoided, from the standpoint of visual comfort. Because of such factors, and because of changes in distance and attitude of the head which arise from adjustment of the chair's elements, it is desirable to provide for compensatory adjustments of the distance, attitude, and angle of the reading stand, relative to the chair elements. The provision of a mount capable of adjustment about an axis or axes parallel to the axis of tilting adjustment of the chair element that supports it (and not coincident with the axis of tilt-

2

ing adjustment, as in Ser. No. 173,074), to the ends indicated, is an object of this invention. By these means the line of vision can be kept more nearly horizontal, the distance from the eyes can be kept that which is most comfortable, and the reading matter can be kept resting upon the reading stand's back, notwithstanding tilting of the chair's back far back from the normal upright position.

10 Likewise, where the reading stand is of the type that can be swung aside, it is an object to provide means to retain it positively against such swinging when it is somewhat overbalanced by tilting of parts to a reclining position, yet by means readily disengaged when it is desired to swing the reading stand aside.

15 It is desirable to provide illumination for the reading matter supported upon such a stand, which is usually done by the provision of a lamp bracket located in front of the stand to illuminate the reading matter placed upon the stand, and because of the various adjustments of the position or attitude of the stand, it is desirable, also, to adjust the illuminating bracket correspondingly, and so that it will not lie in the line of vision, and the provision of a structure to this end is an object of this invention.

20 It is desirable that such a reading stand be removably mounted and separable into smaller units so that it may be taken down and stored away when its use is not desired. The provision of simple dismounting means is one of the objects of this invention, and particularly of such means which will permit the reading stand to occupy a 25 rather small space, notwithstanding its rather extended size when operative. Likewise it is an object to provide complementary contact elements in the separable parts of the reading stand, which will interengage automatically by the correct setting up of the stand, and which will accommodate the relative movements for different adjustments of the parts of the stand.

25 A still further object is the provision of means for assembling the stand in a way which makes it convenient for access to the interior thereof, and particularly to the contact elements, in the event any change of adjustment is necessary.

30 It is also an object to provide a mount for support in an element of the chair itself which will have the capability of adjustment to various positions and which will yet be concealed so that the appearance of the chair is not marred. Additionally, since such a mount incorporates an upwardly open socket, it is an object to provide 35 such mount of this sort which is constructed in

such a way that any foreign matter which may enter the socket may fall or be pushed on through, and will not interfere with the proper assembly of the parts of the stand, nor with the electrical contact elements incorporated in the stand, one set whereof is within the socket.

One further object is the provision of an assembly for the page retainer of the reading stand which will permit ready access to the interior thereof for repair of a broken spring, for example.

Other objects will appear as this specification progresses.

In the accompanying drawings, the invention is shown in a typical form, such as is presently preferred by me.

Figure 1 is a general side elevational view of such a chair, showing the reading stand of the present invention supported thereon and in one position of adjustment relative to the same.

Figure 2 is a view similar to Figure 1, but with parts of the side arm of the chair broken away and shown in section, with the seat and back elements of the chair omitted, and with the reading stand in a position of adjustment somewhat different from that shown in Figure 1.

Figure 3 is a top plan view of one side of the same parts shown in Figure 1, but illustrating only the socket for the reception of the reading stand, and the stand itself removed from the socket.

Figure 4 is an interior side elevation, with parts broken away and shown in section, illustrating the construction of the oscillatable mount in the side arm of the chair for the upright post of the reading stand, and Figure 5 is in general an axial section through the same, the viewpoint being at right angles to that of Figure 4.

Figure 6 is in general a view from the viewpoint illustrated at 6—6 of Figure 4, but showing the socket sectioned.

Figure 7 is in general an axial section along the lateral supporting arm for the stand, showing the interengagement between the stand itself and its supporting arm.

Figure 8 is a sectional view substantially as shown at 8—8 in Figure 7.

Figure 9 is an exploded isometric view with parts broken away and shown in section, illustrating the relationship between the parts of the stand and its lateral supporting arm.

Figure 10 is an axial sectional view through a detail of the stand itself.

Figure 11 is an elevation of the reading stand back and its lamp, from the viewpoint of the chair's occupant.

The chair of the present invention includes two main body-supporting elements, a seat 1, and a back 2, each of which is independently tiltable about a transverse axis A upon a support (not shown) on the floor-engaging frame structure 3, from a nearly horizontal position to a nearly upright position. A side arm 29 is ordinarily secured to tilt with the back 2. The chair may also incorporate a legrest 4 and a headrest 5, each of which is movable relative to the main body-supporting element with which it is associated into various positions by means not shown. Various structures to such ends are illustrated in my several copending applications on the chair per se, and in my issued patents.

The structure of the stand per se is subject to some variation, so far as concerns the remainder of this invention. It is shown as consisting of a circular back 6 having a series of transverse bars 60, the whole constituting a rest

5 for the reading matter. The circular back 6 terminates at its lower end in bifurcated and apertured ears 61, whereby it is supported, or mounted, by a structure which will be described in detail hereinafter, upon the horizontal arm 71 of a support which includes also an upright post 7. The lower end of this post 7 is received in a socket 27 directed radially of an annular mount 28, which is received in a rotative bearing in the side arm 29, for tilting about an axis defined at 26 by the mounting screws which connect the annular member 28, or the socket 27 thereof, to the side plates 25 of the bearing element. The annular member is apertured at 28a and the socket is apertured at 27a, for purposes which will be described hereinafter. Lugs 23, by engaging screw stops 22, limit tilting about the pivot at 26, and springs 21 produce inward pressure on the side plates 25, to retain the mount 28 normally in any intermediate position of adjustment.

20 The post 7 is removably mounted, and its mount permits rotation about the axis of the post, radially of the axis at 26, as well as tilting about the axis at 26. However, for the purpose of retaining the post against undesired rotation about the radial axis, the lower end of the post is notched, as indicated at 72, and the sides of these notches straddle a positioning lug 24, projecting within the socket 27. Disengagement, 25 preparatory to rotation of the post, is radially accomplished by slight outward withdrawal of the notched end from the lug 24, while still retaining the post in the socket 27.

30 It will be observed that the entire reading stand, including the mounting post 7, tilts bodily with tilting of the chair side arm 29 about the axis A, and in addition the annular mount 28, the post 7 which is supported in its socket, and the stand 6 which is supported at the outer end 35 of the post, all may tilt bodily about the axis defined at 26, which axis is radially offset upwardly from the tilting axis A, and not coincident with the axis A, as is the case in Serial No. 173,074. Additionally, the lateral arm 71 may be 40 swung aside by lifting the notch 72 from the positioning lug 24, and then rotating the post 7 to a new position, usually a position 90° removed from its operative position, wherein, in the swung-aside position, the occupant may arise 45 from the chair without interference from the reading stand.

50 In addition, the ring 6 and associated elements may be rotated about the lateral axis of the arm 71; compare, for example, Figures 1 and 2. The lamp 8, which illuminates the reading matter on the stand, is supported upon the end of a bracket arm 80 which, at its inner end, is apertured at 81 so that, received between the furcations 61, this bracket and the stand back 6 are received 55 upon the end of the arm 71 for conjoint rotation, or may be rotated each independently of the other.

60 The detailed structure at this point is shown in Figures 7, 8 and 9. One of the objectives in this particular structure chosen is ease of disassembly when desired, and of reassembly, coupled with ease of adjustment and freedom from the likelihood of accidental disassembly during adjustment. In these views the end of 65 the horizontal arm 71 receives within it a separate tubular connecting member 73 which extends through the apertures in the bifurcated ears 61 of the stand, and which is secured at 74 to a cap 62 which is in effect a part of one of the ears 61, 70 so that cap 62 and member 73 rotate together

relative to the arm 71. The set screw at 74 is inconspicuous, yet readily removable, but when so engaged and so long as the tubular connector 73 is held to the arm 71, disengagement of the parts is prevented. The connector 73 is held to the arm 71, yet permits rotation about the axis of the arm 71 of the stand 6 by means of the spring-pressed button 75 received in some one of the circumferentially spaced holes 76 in the arm 71. By pressing the button 75 inwardly, its rounded projecting end will ride lengthwise within the end of the arm 71 to permit disengagement of the connector 73.

The connector 73 likewise holds the bracket arm 80 in place, and permits angular adjustment of the latter relative to the stand back 6, against frictional resistance between the bracket 80 and the ears 61. The interengagement between the bracket arm 80 and the connector 73 is by means of the bayonet slot 77 entering from the end of the connector 73, and the complementally shaped lug 82 within the aperture 81 of the bracket arm 80. This enables disassembly of the bracket arm 80 from the stand 6 when required, but normally retains them assembled so long as the set screw 74 remains in place. Disassembly for storage merely requires removal of connector 73 from arm 71.

Electrical leads 9 lead from a source through the interior of the chair's side arm 29 to a male dielectric member 90, projecting within the lower end of the socket 27. Part-cylindrical terminals 91a and 91b lie at opposite sides of the member 90, for engagement by jack elements 92a and 92b, mounted in a dielectric mount 93 which is secured within the end of post 7, and thence leads run through the hollow post and its lateral arm 71 to the end of the latter. Such a mount permits rotation of the post 7 about its axis while still retaining correct engagement of the contacts 91a and 92a, 91b and 92b in all operative positions of the reading stand, yet by virtue of the dielectric material between them and its location relative to the contacts 92a and 92b, whenever the reading stand is swung aside to permit the chair's occupant to arise, the arrangement is such that the circuit is interrupted and the lamp at 8 will not stay lit.

At the outer end of the arm 71 the electrical leads engage spring-contact elements 93a and 93b, mounted in the dielectric element 94 which is secured within the end of the arm 71. There they are in position to enter and make contact with the interior walls of complemental part-cylindrical contact elements 95a and 95b (see Figure 7) in the dielectric block 96 which is secured within the end of the tubular connector 73. Thence the leads run through the tubular connector at 73 and the hollow bracket arm at 80, to the lamp at 8. By the construction just described, the stand 6 and its connected parts may readily be disassembled from the arm 71 and may be rotated about the axis of the arm 71 while still maintaining contact, and upon reassembly after disassembly, the whole fits together in the proper manner. All wires are concealed.

One of the transverse elements 60 of the reading stand itself preferably incorporates spring means connected to a retainer cord 61 by which a book B, or similar reading matter, may be held to the reading stand. The cord 61 may be a small steel cable or wire, its ends passing through the grommet 62 in an outward extension 63 at each end of the element 60. The springs 64, which

connect to the opposite ends of the cable 61, are received wholly within the member 63, and the latter has a reduced end 64 which is received within the end of this element 60, and is secured therein by the set screw 66. The latter is inconspicuous and yet by its removal the member 63, 65 may be removed from the end of the transverse element 60 for repair of a broken spring, for instance, or for replacement of a broken cord 61.

The entire arrangement is a neat and convenient one, readily taken apart wherever this may become necessary, for inspection, repair or for simple disassembly into more compact compass, for storage. The electrical connections are automatically and properly made by correct assembly of the parts, and are well protected against accidental short-circuiting. Even the male contact element 90 is so constructed that it is virtually impossible to contact both the terminals 91a and 91b by a nail or hairpin thoughtlessly stuck into the end of the socket 27. Should any foreign matter be pushed into the socket, the latter is open at its lower end at 27a, and such matter will fall through, or can readily be pushed through, and once inside the annular member 28, it will still fall on through the aperture 28a in the bottom of the annular member 28, and thus cannot obstruct proper operation of the parts of the reading stand mount nor the electrical contacts thereof.

I claim as my invention:

1. In combination with a lateral arm, a stand for the support of reading matter having a bifurcated mounting ear apertured for the reception of said arm, for oscillation of the support, a lamp-supporting bracket likewise apertured at one end for the reception of and oscillation about said arm, to be thereby held between the furcations of the stand's ear, a bayonet slot in said arm, and a complemental lug on the bracket, to restrain axial movement of the bracket, and hence of the support, and means removably engaged between the stand's ear and the arm to retain the stand against movement axially relative to the arm.

2. The combination of claim 1, including a tube on the arm interposed between the stand and the bracket, and the arm, and oscillatably mounted in the arm, and latching means interengageable between the tube and the arm to retain the tube, and hence the stand, in any one of several oscillated positions.

3. The combination of claim 2, including complemental contact members, one on the arm, and the other carried by the tube and leading to the bracket-supported lamp, interengageable for operation when the stand, tube, and arm are operatively connected, said contact members being relatively oscillatable while so engaged, to allow adjustment of the stand about the arm's axis.

4. In a reading stand, in combination with an upright back for the support of reading matter, and with a generally horizontal supporting arm whereon said back is supported for rotation,

means for so supporting the back upon the arm including an ear on the back and a connector spindle rotatively mounted upon the arm's terminus, and fixed to said ear, a latch fixed upon one or the other of the connector or the arm, and a plurality of angularly spaced complemental latch-engaging means formed upon the other, and positioned to engage the latch to hold the back in any of a plurality of positions rotated about said arm, and a bracket arm mounted on said connec-

tor spindle, alongside said ear, for rotation with and also independently of said back.

5. In a reading stand, in combination with an upright back for the support of reading matter, and with a generally horizontal supporting arm whereon said back is supported for rotation, means for so supporting the back upon the arm including a pair of spaced apertured ears on the back and a connector spindle rotatively mounted upon the arm's terminus, whereon said ears are slidably and rotatably mounted, means to fix said back to said connector, cooperative latching means upon the connector and arm, respectively, interengageable in a plurality of angularly spaced positions for the support of the back in the several corresponding positions of adjustment, a bracket arm slidable along and pivotally supported on said connector spindle, intermediate said ears, a key formed on said bracket arm, and a bayonet slot formed in the connector spindle, wherein said key is received, to permit rotation of the bracket arm with and also relative to the back, provided the key is within the circumferential extent of the bayonet slot.

6. In a reading stand, in combination with an upright back for the support of reading matter, and with a generally horizontal supporting arm whereon said back is supported for rotation, means for so supporting the back upon the arm including a connector spindle projecting from the back and rotatively and longitudinally slidably engaged with the terminus of said arm, latching means upon the connector and cooperating latching means upon the arm, respectively, one whereof includes elements arranged in a circumferential line, said latching means being interengageable whenever they are in longitudinal registry, in a plurality of angularly spaced positions for the support of the back in the several corresponding positions of adjustment, electrical terminals carried by the arm, and cooperating terminals carried by the connector spindle in position to engage the respective arm-mounted terminals in any rotated position within the limits of the back's adjustment, and so

10

long as the cooperative latching means are in longitudinal registry, but to disengage upon longitudinal movement of the connector spindle from latch-engaging position, and a light in circuit with the connector-mounted terminals, and supported in position to illuminate reading matter supported by said back.

7. The combination of claim 6, including a bracket arm rotatively and slidably mounted upon the connector spindle and operatively connected for movement with the back, longitudinally of the connector, the light being carried by said bracket arm, a key formed on said bracket arm and a bayonet slot formed in said connector spindle, wherein said key is received, the circumferential extent of said bayonet slot being located to permit rotative movement of the bracket arm only when the cooperative latching means are longitudinally in interengaging position.

8. In a reading stand, in combination with an upright back for the support of reading matter, and with a generally horizontal arm whereon said back is supported, a connector rotatively mounted upon and projecting from the terminus of said arm, mounting means formed on said back and slidably received upon said connector, means to secure said mounting means to said connector, a latch fixed upon the connector, and a plurality of angularly spaced latch-engaging means formed upon the arm and positioned to engage the latch to hold the back in any of a plurality of positions rotated angularly about said supporting arm.
